UNITED STATES PATENT OFFICE

JOHN KAHL, OF ST. LOUIS, MISSOURI

AMUSEMENT CAR

Application filed March 5, 1930. Serial No. 433,411.

My invention is an improvement in apparatus designed for special use in amusement parks, and relates more especially to cars or conveyances which are operated over a railway having dips and turns to increase the pleasure and thrill of riding.

The primary object of my invention is to provide a design and construction of railway car of this particular character which will be attractive in appearance to appeal to the aesthetic tastes of the patrons and to which motions are imparted to simulate the movements of the animal or reptile adopted in carrying out the general design or form of the car, in the present instance the shape of the car being in the form of an alligator to illustrate the application of my improved construction.

With this principal object in view my invention contemplates the construction of a car or conveyance for the purpose specified made up of sections intimately connected together in carrying out the form of the animal or reptile, the means of connection between the sections permitting of independent motions thereof to simulate the creeping or crawling movements of the animal or reptile for operation on trucks such as illustrated and described in my prior application for patent filed December 3, 1929, Serial No. 411, 345, by which the desired motions are imparted to the sections.

My present invention therefore consists of a car or conveyance for amusement parks comprising sections joined together by plates and connecting bolts so as to permit of a limited rotatable movement of the sections with respect to each other for use in association with wheeled trucks on which the sections are mounted; all as hereinafter fully described and more specifically set forth in the appended claims:

In the accompanying drawings:

Figure 1 is a side elevation of a car constructed in accordance with my invention.

Fig. 2 is a similar view with parts of the sections broken away to show the interior arrangement.

Fig. 3 is an enlarged detail sectional view

to show the particular form of joint by which the sections are connected together.

Fig. 4 is a section view on the line 4-4 of Fig. 3, and

Figs. 5 and 6 are detail views of the plates forming the joint.

In carrying out my invention the car is made up of two sections 10, 11 one in front of the other and connected together in the particular manner hereinafter described, said sections being preferably in the form of an alligator as illustrated in the drawings although it will be understood that it may represent any other reptile or an animal, in any case said sections being each provided with seats 12 for the occupants of the car and with doors 13 in one or both sides for permitting access to the seats, while the upper part of the car is left open.

For joining the sections together so that they may have an independent rolling motion to simulate the creeping or crawling of the object circular plates 14, 15 are attached to the contiguous ends of said sections and connected centrally by a king-bolt 16 permitting the plates and sections of the car to have a rotating motion limited as to excess movement with respect to each other by means of a series of bolts 17 near the outer edges of the plates, said bolts extending through slots 18 in plate 14 to provide for the required rotatable movement and engaging squared holes 19 in plate 15 beyond which they project to receive nuts 20 secured in place by cotter pins 21. The heads of the bolts bear against the outer side of plate 14 and in order to minimize friction between the bolts and walls of the slots the bolts are provided with sleeves 22. The sections of the car are connected to the plates in the manner shown in Fig. 4, that is to say the inner end of each section is provided with inwardly projecting spaced apart portions 23 secured to the plates by means of screws 24, threaded into holes 25, said attaching portions of the sections being located intermediate the cooperating slots 18 and squared holes 19 receiving the bolts for connecting the plates together, and for the purpose of having the plates turn freely one upon the other ball-bearings 26 are employed,

each set of balls being seated in annular grooves 27 in the plates.

Each section of the car is mounted on a wheeled truck 28 traveling over rails 29, and the trucks may be of ordinary construction when the lateral rocking movement is imparted to the sections by having the tracks slightly rolling instead of straight, but I prefer to use the trucks of the construction shown 10 and described in my prior application hereinbefore mentioned as it provides for rocking the frame of the truck to permit of the use of a straight track, and in using the cars in the equipment of an amusement park several are 15 connected in a train for which purpose the outer end of each section is provided with a universal joint 30 of a conventional type having oppositely projecting drawbars 31 on which springs 32 are mounted and interposed 20 between the joint and end of the section of the car, said drawbars working in sleeves 33 secured to the car so that the springs will overcome any jams or jars in the running of the train.

25 As will be obvious from the foregoing description in connection with the accompanying drawings, my invention provides for the construction of a car in sections joined together in such manner that the assembled sections, constructed in the form of an animal or a reptile, when mounted on trucks of the type shown and described in my co-pending application may have lateral rocking motions in opposite directions imparted to the sections 30 to not only give to the object the appearance that it is creeping or crawling but also add to the pleasure of the occupants, the particular construction of the joints insuring a secure connection and limiting the movements of 35 the sections so as to add to the safety of the car, it being understood of course that each car may be made up of more than two sections and that the couplings provide for making up a train of a plurality of cars either of 40 the same design or of different designs.

45 Having described my invention I claim:

1. A car for amusement parks comprising sections joined together at the center to provide for rotatable movements of the sections 50 one with respect to the other.

55 2. A car for amusement parks comprising sections joined together at the center to provide for rotatable movements of the sections one with respect to the other, and means for limiting the rotatable movements of said sections.

60 3. A car for amusement parks comprising a plurality of sections mounted on wheeled trucks, plates secured to the contiguous ends 65 of said sections, and a king bolt connecting the plates together to permit rotatable movements of the sections one with respect to the other.

65 4. A car for amusement parks comprising a plurality of sections mounted on wheeled

trucks, plates secured to the contiguous ends of said sections, a king bolt connecting the plates together at the center to permit rotatable movements of the sections one with respect to the other, and means for limiting the movements of the plates upon each other. 70

5. A car for amusement parks comprising a plurality of sections mounted on wheeled trucks, plates secured to the contiguous ends of said sections, a king bolt connecting the 75 plates together at the center to permit rotatable movements of the sections one with respect to the other, means for limiting the movements of the plates upon each other, and anti-friction ball bearings interposed between the plates. 80

6. A car for amusement parks comprising a plurality of sections mounted on wheeled trucks, plates secured to the contiguous ends of said sections, a king bolt connecting the 85 sections together at the center to permit rotatable movements of the sections one with respect to the other, and bolts connecting the plates together near their outer edges, said bolts passing through slots in one of the 90 plates to limit the movement of the plates upon each other.

7. A car for amusement parks comprising a plurality of sections mounted on wheeled trucks, plates secured to the contiguous ends 95 of said sections, a king bolt connecting the sections together at the center to permit rotatable movements of the sections one with respect to the other, and bolts connecting the plates together near their outer edges, said 100 bolts passing through slots in one of the plates to limit the movement of the plates upon each other; together with drawbars carrying one section of a universal joint, and 105 springs interposed between said joint and end of the car.
